UNITED STATES PATENT OFFICE.

BERNARD J. DE PASSE, OF NEW YORK, N. Y.

DESIGN FOR A PLATE OR SIMILAR ARTICLE.

Application filed September 26, 1923. Serial No. 7,325. Term of patent 3½ years.

To all whom it may concern:

Be it known that I, BERNARD J. DE PASSE, a citizen of the United States, and a resident of New York, in the county of New York and State of New York (whose post-office address is 130 Pearl Street, New York, N. Y.), have invented a new and original ornamental Design for a Plate or Similar Article, of which the following is a specification, reference being had to the accompanying drawings, forming a part thereof.

Referring to the drawings:

Fig. 1 is a plan view of a plate embodying my design.

Fig. 2 is a fragmentary part or segment of the design on a larger scale than Fig. 1.

I claim:

An ornamental design for a plate or similar article as represented in the accompanying drawings.

BERNARD J. DE PASSE.
